CAR COUPLER OPERATING MEANS

Arthur J. Bazeley, Cleveland, Ohio, assignor to
 National Malleable & Steel Castings Company,
 Cleveland, Ohio, a corporation of Ohio

Application August 21, 1930. Serial No. 476,799

5 Claims. (Cl. 213—169)

This invention relates to car couplers and more particularly to couplers of the bottom-operated type. A prime object of the invention is the provision of means whereby the coupler lock may be operated with greater facility than heretofore and with less wear upon the operating parts. The invention also comprises other features which will be hereinafter described and claimed.

In the accompanying drawings:

10 Fig. 1 is a view in front elevation, and

Figs. 2 and 3 are views in side elevation, of an uncoupling mechanism embodying my invention; the coupler knuckle being closed in Fig. 2 and open in Fig. 3.

15 Fig. 4 is a plan view, while

Figs. 5 and 6 are views of details.

Referring to the drawings, the numeral 2 designates an uncoupling rod rotatably supported in brackets 3, 3 on the car structure 4. A rod 5 provided with a handle portion 6 is journaled near one end in a bracket 7 and is operatively connected at its other end to said rod 2 through the engagement of an eye 8 on hook shaped portion 9 of rod 5 with a portion of the rod 2 adjacent an extension 10 thereof. If desired, another rod 5 may be connected with the other end of rod 2, as shown in Fig. 4, so that the coupler lock may be operated from either side of the car. A lever 11 which may be of any suitable design for lifting the lock of the coupler 12 is pivotally mounted on the bottom of said coupler through trunnion 13. The lever 11 may conveniently comprise a bearing portion 11' fitting over the trunnion 13, and an arm 11² connected to a link 11³ for actuating the lock in the usual manner well understood in the art.

In carrying out my invention I provide a pivotally mounted member 14 which is adapted to receive a plunger 15 for operating the lever 11.

40 Member 14 is shown pivoted to a bracket 16 which may be mounted on a coupler guide casting or on the underframe of the car, and is provided with a slot 17 through which the plunger 15 extends. Said plunger is connected to the

45 lock actuating lever 11 through the engagement of hook portion 18 of said plunger with eye 19 of said lever. When the parts are in the normal unoperated position shown in Figs. 1 and 2, the plunger 15 rests in the widened lower portion of 50 the slot 17 in member 14 (as shown in Fig. 5) whereby said plunger may slide freely in said slot in response to movements of the coupler with respect to the car in draft and in buff.

When the handle 6 of the rod 5 is swung away 55 from the car, the portion 9 of said rod engages

extension 10 of rod 2, thereby rotating said rod in the brackets 3. During the initial portion of the rotation of the rod 2 the clearance normally existing (Figs. 1 and 2) between said rod and the plunger 15 is taken up and said plunger is forced upwardly by said rod into firm engagement with the upper narrow portion of the slot 17. As rotation of the rod 2 continues the plunger 15 is moved upwardly and forwardly by said rod, thereby rotating the lock lift lever 11 and raising the coupler lock. The plunger supporting member 14 swings freely about its pivot and moves with the plunger 15 as a unit as said plunger is actuated for operating the lock. Through the pivotal mounting of member 14 I avoid the slippage between the plunger and said member which would result during operation of the plunger by rod 2 if said member were rigid with the car frame. It will be noted that during the operation of the plunger 15 by the rod 2 said rod exerts an upward pressure against said plunger, forcing the latter against the upper sides of the hole in the member 14; and in the prior constructions, wherein the plunger extended through a hole in a member rigid with the car frame, the dragging of the plunger over the upper side of the hole, against the force maintaining the plunger in contact therewith, resulted in substantial waste of energy and in difficult operation. With my arrangement 75 wherein the member 14 is pivoted, and moves with the plunger as a unit, slippage between said plunger and said member during operation of the plunger to actuate the lock is obviated. Loss of power due to slippage between said 80 plunger and member while the plunger is acted upon by the rod 2 is thus avoided and the actuation of the coupler lock is facilitated. In addition, wear upon said plunger and member by movement of the plunger for operating the lock 85 is eliminated. A further advantage in the pivotal mounting of the member 14 resides in the fact that the plunger is thereby permitted to swing upwardly about the pivotal axis of said member, thus permitting rod 2 to have a longer 100 stroke in operating the lock than if member 14 were fixed. Such increased stroke of itself permits the exertion of less force to accomplish the work of operating the lock.

The brackets 3 in which the rod 2 is journaled 105 may be conveniently formed as shown in Fig. 6. As there shown, each of said brackets may comprise a portion 20 having holes 21 for the reception of bolts or screws 22 (Figs. 2 and 3) for securing the bracket to the underside of the 110

car frame, and a socket or bearing portion 23 for receiving the rod 2. Lips 24 spaced from each other and extending beyond said bearing portion 23 are provided with openings 25 for the reception of a bolt 26 (Figs. 1, 2, and 3) for retaining the rod 2 in said bearing portion.

The bracket 16 for the member 14 may comprise a portion 27 having holes for the reception of bolts or screws 28 for securing said bracket to the underframe of the car, and a bearing portion 29 in which the upper portion 30 of member 14 is received. A bolt 31 extends through said bearing portion 29 and through said portion 30 of member 14, said bolt serving as a pivot for said member 14 whereby said member is pivotally retained in said bearing portion.

A further feature of my invention comprises the provision of a flattened portion 32 on the plunger 15 for engagement by the rod 2. In order to provide adequate clearance for avoiding interference by the coupler guide casting with movement of the plunger 15 for operating the lock lift lever 11 in various positions of the coupler, said plunger as shown in Figs. 2 and 3 is bowed downwardly between the supporting member 14 and the lock lift lever 11. When pressure is applied to plunger 15 by rod 2, said plunger tends to rotate laterally of the coupler and to assume a position wherein it would be bowed upwardly. By providing the widened portion 32 aforesaid, lateral movement of the plunger is prevented. The underside of said widened portion is flat, and thus if the rod 2 tends to swing the plunger to one side a point contact is made between said rod and plunger and a lateral component of force is set up in the opposite direction whereby the plunger is restored to its proper position.

It will be noted that the member 14 in its normal position (Fig. 2) extends slightly forward from its pivot. Said member is held in this position by the engagement of a lug 35 on the member 14 with projections 33, 33 (Figs. 2, 3, and 5) on said bracket. It will be seen that if member 14 were normally inclined to the rear of the vertical center line of its pivot it would be necessary that said member move downwardly to the bottom of its arc of travel before it could move upwardly in the same direction as uncoupling lever 11. The necessity for such downward movement is avoided by the means above described whereby said member is retained in forwardly inclined position.

The upper portion of member 14 is provided with ribs 34 (Figs. 2, 3, and 5), which, in co-operation with the projections 33 on bracket 16, prevent the application of said member to said bracket in such position that said member becomes inoperative. Through said ribs 34 the application of member 14 to said bracket in proper position for cooperating with the plunger 15 is assured. It will be apparent from Figure 2 that if the member 14 were applied in a rearwardly rocked position the ribs 34 would compel it to be held at such a large angle to the vertical that the element 15 could not be passed through the opening 17 and at the same time be connected with the eye 19. Assembly of the parts with the

member 14 in this improper position is thus effectively prevented. For purposes of symmetry ribs 34' similar to ribs 34 and a lug 35' similar to lug 35 may be provided on the other side of member 14, as shown in Fig. 5.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

I claim:

1. Coupler operating mechanism comprising a lock lift lever, an element connected to said lever for operating the latter, a pivoted member having a slot receiving said element, said slot having an upper narrowed, wedging portion and also having a lower widened portion in which said element is received when in normal unoperated position, and means comprising a manually operable rod for forcing said element into wedging engagement with the upper narrowed portion of said slot and for causing said element and said member to swing in unison to actuate said lever.

2. Coupler operating mechanism comprising a lock lift lever, an element connected to said lever for operating the latter, a pivotally mounted member for supporting said element, said member having a slot with an upper narrowed, wedging portion and a lower widened portion, said element, when in normal unoperated position extending through the lower widened portion of said slot, and means for forcing said element into wedging engagement with the upper narrowed portion of said slot as a preliminary to actuation of said lever for lifting the lock.

3. Coupler operating mechanism comprising a lock lift lever, an element connected to said lever for operating the latter, a manually operable rod for actuating said element, a pivotally mounted member for supporting said element and movable with said element during its actuation by said rod, and means for maintaining said member inclined forwardly from its pivot.

4. Coupler operating mechanism comprising a lock lift lever, an element connected to said lever for operating the latter, a manually operable rod for actuating said element, a member for supporting said element and movable with said element during its actuation by said rod, means pivotally supporting said member, and interengaging means between said first mentioned means and said member for preventing movement of said member rearwardly of its pivot.

5. Coupler operating mechanism comprising a lock lift lever, an element connected to said lever for operating the latter, a manually operable rod for actuating said element, a member for supporting said element and movable with said element during its actuation by said rod, means for pivotally supporting said member in a forwardly inclined position, and means preventing assembly of the parts with said member applied to said supporting means in a rearwardly inclined position.

ARTHUR J. BAZELEY.
